ROLLER-BED TRAILER

Shusuke Shimoji, Ichikawa, Japan, assignor to Kabushiki
Kaisha Tokyo Suchiro Sharyo Seisakusho, Tokyo, Japan

Filed Dec. 4, 1970, Ser. No. 26,297

Term of patent 14 years

Int. Cl. D12—10

U.S. Cl. D14—3

FIG. 1

FIG. 2

FIG. 3

FIG. 4

FIG. 1 is a perspective view of a roller-bed trailer showing my new design as seen from the front, top and right sides;

FIG. 2 is a top view;

FIG. 3 is a right side view; and

FIG. 4 is a front view.

The rear of the roller-bed trailer is identical in appearance with the front, and the side not shown is identical in appearance with the side shown in the drawing.

I claim:

The ornamental design for a roller-bed trailer, as shown and described.
